UNITED STATES PATENT OFFICE

115,958

DESIGN FOR AN ELECTRIC STEAMING IRON

Louis V. Eckstein, St. Louis, Mo., assignor to
Steem-Electric Corporation, St. Louis, Mo., a
corporation of Missouri

Application May 12, 1939, Serial No. 84,955

Term of patent 7 years

To all whom it may concern:

Be it known that I, Louis V. Eckstein, a citizen of the United States, residing in the city of St. Louis and State of Missouri, have invented a new, original, and ornamental Design for Electric Steaming Irons, of which the following is a specification, reference being had to the accompanying drawing, forming part thereof.

In the drawing:

Figure 1 is a perspective view of the electric steaming iron showing my new design, the iron being viewed from the front.

Figure 2 is a front view; and

Figure 3 is a rear view.

I claim:

The ornamental design for an electric steaming iron, as shown.

LOUIS V. ECKSTEIN.
